2,417,411

DEVICE FOR RECIPROCATING PUMP RODS

Louis P. Heiman, St. Paul, Minn.

Application February 12, 1945, Serial No. 577,471

18 Claims. (Cl. 74—37)

1

This invention relates to a driving means for a reciprocating member such as a reciprocating member for operating a pump rod.

It is an object of this invention to provide a simple, efficient and compact means for moving a reciprocating member in opposite directions.

It is a further object of the invention to provide an efficient mechanism for reciprocating a member comprising a pair of oscillatable or rotatable members connected respectively to said reciprocating member and adapted to be alternately oscillated or rotated in opposite directions for operating said reciprocating member.

It is a further object of the invention to provide a structure such as set forth in the preceding paragraph also comprising a constantly driven rotatable member, a second rotatable member adjacent the latter, means connecting said second rotatable member and one of said oscillating members for moving the latter in reverse direction to said second rotatable member, together with means carried by the other oscillating member and said second rotatable member adapted to be moved into driving relation with said driven rotatable member and cam means for moving said last mentioned members.

It is still another object of the invention to provide a mechanism for operating a reciprocating member comprising a pair of oscillating or rotating members connected respectively to said reciprocating member for operating the latter, a constantly driven rotatable member adjacent one of said oscillating members, a second rotatable member adjacent said driven rotatable member, means connecting said second rotatable member to the other of said oscillating members for driving the latter in reverse direction to said second rotatable member, said driven rotatable member having driving means at opposite sides thereof, members carried respectively in said one oscillating member and said second rotatable member adapted to be moved alternately into driving relation with said driving means on said driven rotatable member and stationary cams at the remote sides of said one oscillating member and said second rotatable member for moving said last mentioned members to alternately connect said one oscillating member and said second rotatable member to said driven rotatable member.

It is still further an object of the invention to provide such a mechanism as set forth in the preceding paragraph, said driven rotatable member having a member carried therein and movable transversely thereof adapted to alternately engage and move said members carried in

2

said one oscillating member and said second rotatable member and being moved by cams carried respectively on said one oscillating member and said second rotatable member for disconnecting the same from said driven rotatable member.

These and other objects and advantages of the invention will be fully set forth in the following description made in connection with the accompanying drawings in which like reference characters refer to similar parts throughout the several views and in which:

Fig. 1 is a vertical section taken substantially on line 1—1 of Fig. 2, as indicated by the arrows;

Fig. 2 is a view partly in side elevation and partly in vertical section taken on line 2—2 of Fig. 1, as indicated by the arrows;

Fig. 3 is a partial vertical section taken on line 2—2 of Fig. 1, as indicated by the arrows; 20 with parts in different position;

Fig. 4 is a horizontal section taken substantially on line 4—4 of Fig. 1; as indicated by the arrows;

Fig. 5 is a view similar to Fig. 4 showing some 25 of the parts in different positions;

Fig. 6 is a view similar to Fig. 4 showing some of the parts in still other positions;

Fig. 7 is a partial view in side elevation as seen from the left of Fig. 1.

Fig. 8 is a vertical section taken on line 8—8 30 of Fig. 5, as indicated by the arrows; and

Fig. 9 is a vertical section taken on line 9—9 of Fig. 5, as indicated by the arrows.

Referring to the drawings, a structure is shown 35 comprising a base member 15 to one end of which are secured by headed bolts 16 a plurality of brackets 17. Brackets 17 engage and support vertically extending oppositely disposed channel members 18 between which is guided for movement a cross-head 19. A pump rod 20 is secured in cross-head 19, the same having a nut 21 threaded thereon engaging the lower side of said cross-head and having a nut 22 threaded thereon engaging the other side of said cross-head. At one 40 side said cross-head has bolted thereto by headed bolts 24 a clamping plate 25. Clamping plate 25 clamps and connects to cross-head 19 a flexible member or cable 26 illustrated as disposed in and moving in the peripheral groove 28a of an oscillatable or rotatable segmental pulley or sheave 28. Member 26 is clamped to member 28 adjacent one end of said groove 28a by a U-bolt 27 passing through lugs 28b and equipped with nuts 29. Plate 25 also clamps and connects to cross-

55 head 19 another flexible member or cable 31 illus-

trated as adapted to be disposed in and movable in a peripheral groove 32a of a second segmental pulley or sheave 32. Member 31 is secured adjacent one end to member 32 adjacent one end of groove 32a by a U-bolt 34 passing through lugs 32b and equipped with nuts 35. Member 28 is secured to a shaft 38 in any suitable manner as by a key 39 and set screw 43. Shaft 38 is journaled in bearing hubs 40a and 41a carried respectively on plates or brackets 40 and 41 which extend vertically from and are connected to and shown as integral with base plate 15. Brackets 46 are riveted to base 15 and have vertical flanges 46a riveted to plates 40 and 41 respectively. Pulley or member 32 is revolvable on a shaft 44 carried in bearing hubs 40b and 41b formed on plates 40 and 41 respectively. Shaft 44 is held stationary in any suitable manner as by pins or screws 45 extending through hubs 40b and 41b thereinto.

Spaced brackets 47 are secured to base member 15 by headed screws or bolts 48 and a shaft 49 is journaled in said brackets. Shaft 49 is shown as extending to one side of one of said brackets 47 and will be connected to some suitable driving means or motor. Secured to shaft 49 between brackets 47 is a worm gear 50. Worm gear 50 meshes with a worm wheel gear 52 which is revolvable on shaft 44. A second gear 53, shown as a spur gear, is journaled on shaft 44 and meshes with another spur gear 54 secured to a shaft 56 journaled in a bearing hub 40c carried on bracket 40. Shaft 56 is held from longitudinal movement in one direction by a collar 57 secured thereto in any suitable manner as by a set screw 58. Shaft 56 has secured thereto at one side of gear 54 and is held from longitudinal movement in one direction by a sprocket 60. Sprocket 60 is secured to shaft 56 in any suitable manner as by a pin 61. A chain 62 runs over sprocket 60 and over a sprocket 63 secured to shaft 38 in any suitable manner as by a set screw 64. As shown in Fig. 1, sprocket 63 has a hub, one of the ends of which engages the hub of member or sheave 28 and the other end of which engages hub 40a. With the described construction it will be seen that shaft 38 will be driven by chain 62 and gear 54 in a reverse direction to the rotation of gear 53.

The driven rotatable member or worm wheel gear 52 has lugs 52a and 52b projecting from opposite sides thereof respectively and these lugs are adapted to engage a member or key 66 disposed in a slot in gear 53 and movable therein transversely of gear 53. The oscillating member or sheave 42 also has carried therein a member or key 67 slidable in a slot extending transversely of said sheave and adapted to be moved into position to be engaged by lug 52a. The driven worm wheel gear 52 also has therein a member or key 68 slidable in a slot extending transversely thereof. The frame members 40 and 41 are apertured to have inserted therein respectively cam plates 40c and 41c which are held in place by headed bolts 70 threaded into flanges on plates 40c and 41c, which flanges are disposed at the inner sides of plates 40 and 41. The cam plate 40c has a cam 40d thereon adapted to be engaged by and to move the key 66 in the rotation of gear 53. Cam plate 41c has a cam 41d thereon adapted to be engaged by and to move the key 67 in the rotation of member or sheave 32. The gear 53 also carries thereon a cam 53a adapted to engage and move key 68 in the rotation of gear 53. The member or sheave 32 also carries a

cam 32b on the hub thereof which is adapted at times to engage and move key 68.

In operation shaft 49 will be driven by a motor or other suitable driving means and worm gear 50 will thus be driven to rotate the worm wheel gear 52. Gear 52 will thus be constantly driven in one direction. As gear 52 rotates, the key 66 will at one time be moved to the position shown in Fig. 4, in which position it is moved into alignment with lug 52b. When in this position gear 53 will be rotated by lug 52b engaging key 66 and thus moving it and rotating gear 53. Key 66 is moved to the position shown in Fig. 4 by the cam 40d on the cam plate 40c. When key 66 is thus moved, gear 53 is moving in the direction indicated by the arrow adjacent the same in Fig. 4. Just after key 66 is moved to said position and before it is engaged by lug 53a, the cam 53a on gear 53 engages the key 68 in gear 52 and moves the same away from gear 53. When key 68 is so moved, it is in alignment with key 67 and as key 68 is thus moved away from gear 53, key 67 is also moved and is moved toward cam plate 41c or downward, as shown in Figs. 4, 5 and 6. The driven gear 52 now drives gear 53 and the same is disconnected from sheave 32. Gear 53 being rotated, sprocket 60 is rotated, moving chain 62 and rotating sprocket 63, shaft 38 and sheave 28. Sheave 28 is rotated in a clockwise direction, as seen in Fig. 2, and it winds up cable 26 thereon, thus raising cross-head 19 and pump rod 20. When sheave 28 is thus rotating in a clockwise direction, sheave 32 is disconnected from gear 52 and is moved by cable 31 to the position shown in Fig. 2, the same moving idly on shaft 44. Just before sheave 28 reaches the position shown in Fig. 2, the cam 32b on sheave 32 engages key 68 in gear 52 and moves it toward gear 53. Key 68 at this time is in alignment with key 66 and key 66 is moved or pushed by the key 68 to the position shown in Fig. 5. Key 66 is thus not in driving relation with lug 52b and the driving of gear 53 is discontinued. Just before keys 68 and 66 are moved to the position shown in Fig. 5, key 67 engages cam 41d on cam plate 41c and is moved by said cam into the position shown in Figs. 5 and 6. Key 67 is now in alignment with lug 52a and is in driving relation to gear 52 and sheave 32, will now be driven by gear 52. Sheave 32 will be driven in a counter-clockwise direction and cable 31 will be wound on sheave 32 and will thus be moved downward moving cross-head 19 and pump rod 20 downward. When sheave 32 is thus being driven, gear 53, as stated, is disconnected from gear 52 and sheave 28, sprocket 63, chain 62, gear 54 and gear 53 will be rotated by cable 26, rotating sheave 28. Gear 53 will turn idly on shaft 44. When sheave 32 has made substantially a half revolution, the cam 53a on gear 53 will engage key 68 and will move the same away from gear 53. Key 68 at this time is in alignment with key 67, as shown in Fig. 6, and key 67 will be pushed away from gear 52 and will be moved out of alignment with lug 52a. Just before key 67 is thus moved, the key 66 will be engaged by cam 40d on cam plate 40c and will again be moved to the position shown in Fig. 4. Sheave 32 is now disconnected from gear 52 and the gear 53 is again connected to gear 52. The sheave 28 will again be moved as above described and will pull cable 26, cross-head 19 and pump rod 20 upwardly. It will be seen that the cam 41d on cam plate 41c is disposed substantially 180 degrees from the cam 40d carried on cam

plate 40c. The cam 32b when in operative position to engage key 68 is somewhat separated circumferentially from cam 41d. The key 68 is thus moved just after the key 67 or the key 66 is moved into driving position. The cam 53a is thus also somewhat spaced circumferentially from cam 40d when it is acting on key 68, as shown in Fig. 9. Key 66 is thus moved out of driving relation to gear 52 just after key 67 is moved into driving relation with gear 52, but before lug 52a engages key 67. Vice versa key 67 is moved out of driving position relative to gear 52 just after key 66 is moved into driving relation but before lug 52a engages key 66. In Fig. 5 key 67 has just been moved into driving position and cam 32b is just finishing its movement of keys 68 and 66 to disconnect gear 53. In Fig. 4 key 67 is just being moved by cam 41d into driving position but cam 32b has not yet reached key 68 to move it and key 66 to disconnect gear 53. Key 68 will complete the movement of key 66 just before lug 52a engages key 67 to drive sheave 32. As gear 53 rotates in a counter-clockwise direction in its idling cycle, key 66 first engages cam 40d and is moved into driving position. Shortly afterward, as can be seen in Fig. 9, cam 53a will move keys 68 and 67 and disconnect sheave 32 just before lug 53a engages key 66 to pick up and drive gear 53. It will thus be seen that the sheaves 28 and 32 are alternately driven or oscillated in opposite directions to move the cross-head 19 and pump rod 20.

From the above description it will be seen that I have provided quite a simple, rugged and very efficient driving means for reciprocating a member such as a pump rod. The reversal of the reciprocating members is accomplished easily and smoothly. The device when used to reciprocate a pump rod is of particular utility in deep well pumps or pumps used in mines. In certain deep well pumps the water is raised through several cylinders. When the pump rod moves upward water is lifted on such up-stroke to an upper cylinder and it is discharged from the upper cylinder on the down-stroke. Both strokes thus require power and the present mechanism drives with as much power in one direction as in the other. The amplitude of reciprocation can be varied by varying the radius of the oscillating sheaves. The circumferential movement of the sheaves can also be varied by varying the disposition of the cams. The power is evenly applied over the entire travel in both directions and a smooth operation of the pump rod is thus secured. A long stroke can be had on the pump rod which will eliminate cylinder wear and give longer life to packing, valves, etc. The direct straight line pull also eliminates bending stresses in the pump rod. Crank pins, connecting rods and the necessary bearings commonly used in pump operating reversing mechanisms are eliminated. The reciprocated motion could be applied to various machines such as saws, slotters, shapers, planers, grinders, hoists and elevators. Obviously it could be used to translate rotary into reciprocating motion in various applications. The reciprocating motion obtained is of constant speed and the reversal is accomplished without any jerky effect. The stroke in one direction could be made of a different speed than the stroke in the opposite direction by varying the ratio of the sprockets over which the chain runs. The device has been amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A pump operating mechanism having in combination, a vertically reciprocating pump element, an oscillating member connected to said element for moving it in one direction, a second oscillating member connected to said element for moving it in the opposite direction, a driven rotating member having driving means thereon, a second rotatable member at one side of said driven rotatable member, means connecting said second rotating member and said first mentioned oscillating member to cause the latter to move in reverse direction to said second rotatable member, means carried by said second oscillating member and said second rotatable member adapted to be moved alternately respectively into engaging relation with said driving means, and cam members for moving said last mentioned means to alternately connect said second mentioned oscillating member and said second rotatable member to said driven rotatable member.
2. The structure set forth in claim 1, and means carried in said driven rotatable member for moving said third mentioned means.
3. A pump operating mechanism having in combination, a vertically reciprocating pump element, an oscillating member connected to said element for moving it in one direction, a second oscillating member connected to said element for moving it in the opposite direction, a driven rotating member having driving means thereon, a second rotatable member adjacent said driven rotatable member at the side thereof opposite said second oscillating member, means connecting said second rotating member and said first mentioned oscillating member for rotating the latter in reverse direction to said second rotating member, said driven rotatable member having driving means at opposite sides thereof, members carried in said second mentioned oscillating member and said second rotatable member respectively adapted to be alternately moved into position to be engaged by the driving means at one side of said driven rotatable member, and cam means for moving said last mentioned members to alternately connect said second oscillating member and said second rotatable member to said driven rotatable member.
4. The structure set forth in claim 3 and a member carried in said driven rotatable member and movable transversely thereof adapted to cooperate with said last mentioned members to move the latter, and cam means for moving said last mentioned member.
5. A pump operating mechanism having in combination, a vertically reciprocating pump element, an oscillating member connected to said element for moving it in one direction, a second oscillating member connected to said element for moving it in the opposite direction, a driven rotating member having driving means thereon, a second rotatable member at one side of said driven rotatable member adjacent said second oscillating member, a second rotatable member adjacent said driven rotatable member at the side thereof opposite said second oscillat-

ing member, means connecting said second rotatable member and said first mentioned oscillating member for rotating the latter in reverse direction to said second mentioned rotatable member, said driven rotatable member having driving means at opposite sides thereof, members carried in said second mentioned oscillating member and said second rotatable member respectively adapted to be alternately moved into position to be engaged by the driving means at one side of said driven rotatable member, stationary cam means at the sides respectively of said second mentioned oscillating member and said second rotatable member remote from said driven rotatable member for alternately moving said last mentioned members respectively to bring the same into driving relation with said driving means on said driven rotatable member to alternately drive said second mentioned oscillating member and said second rotatable member.

6. The structure set forth in claim 5, a member carried in said driven rotatable member and movable transversely thereof adapted to engage said last mentioned members respectively to move the same out of driving relation to said driving means on said driven rotatable member and cam means carried respectively on said second mentioned oscillating member and second rotatable member for moving said last mentioned member.

7. A device of the class described, having in combination, a vertically reciprocating element, an oscillating member connected to said element for moving it in one direction, a second oscillating member connected to said element for moving it in the opposite direction, a driven rotatable member adjacent said second oscillating member and having lugs projecting at opposite sides thereof, a second rotatable member adjacent said driven rotatable member, means connecting said second rotatable member and said first mentioned oscillating member for rotating the latter in reverse direction to said second mentioned rotatable member, keys carried in said second mentioned oscillating member and said second rotatable member respectively extending transversely thereof and adapted to be moved alternately into position to be engaged by said lugs respectively, stationary cam means at the sides respectively of said second mentioned oscillating member and said second rotatable member for alternately moving said keys respectively to bring the same into driving relation with said lugs to alternately drive said second mentioned oscillating member and said second rotatable member.

8. The structure set forth in claim 7, a key carried in said driven rotatable member and movable transversely thereof adapted to engage said keys respectively to alternately move the same out of driving relation with said lugs and cam means carried respectively on said second mentioned oscillating member and said second rotatable member for engaging and moving said last mentioned key.

9. A device of the class described having in combination, a reciprocating element, an oscillating member connected to said element for moving it in one direction, a second oscillating member connected to said element for moving it in the opposite direction, a driven rotatable member adjacent said second oscillating member and having driving means at opposite sides thereof, a second rotatable member adjacent said driven rotatable member, said second oscillating member, said driven rotatable member and said sec-

ond rotatable member being journaled on a shaft, means connecting said second rotatable member and said first mentioned oscillating member to cause the latter to move in reverse direction to said second rotatable member, means carried by said second oscillating member and said second rotatable member adapted to be moved alternately respectively into engaging relation with said driving means and cam members for moving said last mentioned means to alternately connect said second mentioned oscillating member and said second rotatable member to said driven rotatable member.

10. The structure set forth in claim 9, said second rotatable member constituting a gear, a gear meshing with said gear, a sprocket connected to said last mentioned gear, a sprocket connected to said first mentioned oscillating member and a chain running over said sprockets.

20 11. A device of the class described having in combination, a reciprocating element, an oscillating member connected to said element for moving it in one direction, a second oscillating member connected to said element for moving it in the opposite direction, a driven rotatable member having driving means at opposite sides thereof, said second oscillating member being disposed at one side of and adjacent said driven rotatable member, a second rotatable member at the opposite side of and adjacent said driven rotatable member, means connecting said second rotatable member and said first mentioned oscillating member to cause the latter to move in reverse direction to said second rotatable member, movable means for alternately connecting said second rotatable member and said second oscillating member to said driving means and cam members for operating said last mentioned means.

12. The structure set forth in claim 11, a shaft, said second oscillating member, said driven rotatable member and said second rotatable member being journaled on said shaft.

13. A device of the class described having in combination, a reciprocating element, an oscillatable sheave adjacent said element, a cable secured to said sheave and to said element, means for rotating said sheave to wind said cable thereon and move said element in one direction, said cable moving adjacent and parallel to the line of movement of said element, a second oscillatable sheave, a second cable secured to said second sheave and to said element, and means for rotating said second sheave alternately with the movement of said first mentioned sheave and in a direction opposite to that of said first mentioned sheave to move said element in the opposite direction, said second cable moving adjacent and parallel to the line of movement of said element.

14. The structure set forth in claim 13, said last mentioned means comprising a driven member, and means for alternately connecting said sheaves to said member.

15. The structure set forth in claim 13, a driven member rotating constantly in one direction, a gear at one side of said member, one of said sheaves being at the opposite side of said member, means connecting said gear to the other of said sheaves and cam operated means for alternately connecting said gear to said driven member and for connecting said last mentioned sheave to said driven member.

16. A device of the class described having in combination, a shaft, a driving gear secured to said shaft, an oscillating sheave journaled on said shaft at one side of said gear, a reciprocating

member, means connecting said sheave to said member to move said member in one direction, a second gear journaled on said shaft at the opposite side of said driving gear, means for alternately connecting said sheave and gear to said driving gear, a second shaft, a third gear on said second shaft and meshing with said second gear, a third shaft, a second oscillating sheave secured to said third shaft, means connecting said second sheave to said reciprocating member to move it in a direction opposite to said direction, sprockets on said second and third shafts and a chain running over said sprockets.

17. The structure set forth in claim 16, said first mentioned means comprising a cable secured to said first mentioned sheave and adapted to be wound thereon, said cable being also secured to said reciprocating member and said last mentioned means comprising a cable secured to said second sheave and adapted to be wound thereon and also secured to said reciprocating member.

18. A device of the class described having in combination, a shaft, a driving gear secured to said shaft, an oscillating sheave journaled on said

shaft at one side of said gear, a reciprocating member, means connecting said sheave to said member to move said member in one direction, a revoluble member journaled on said shaft at the opposite side of said driving gear, means for alternately connecting said sheave and revoluble member to said driving gear, a second shaft, a second oscillating sheave carried on said second shaft, means connecting said revoluble member and sheave to rotate said sheave, and means connecting said second sheave to said reciprocating member.
